FIG. 5 is a photographic bottom view thereof;

FIG. 6 is a photographic top view thereof;

FIG. 7 is a photographic front, right, and top perspective view thereof;

FIG. 8 is an enlarged, photographic, partial front view thereof;

FIG. 9 is a photographic front view of a further embodiment of the wristwatch of the present invention showing our new design;

FIG. 10 is a photographic rear view thereof;

FIG. 11 is a photographic left side view thereof;
FIG. 12 is a photographic right side view thereof;
FIG. 13 is a photographic bottom view thereof;
FIG. 14 is a photographic top view thereof;
FIG. 15 is a photographic front, right, and top perspective view thereof;
FIG. 16 is an enlarged, photographic, partial front view thereof;
FIG. 17 is a photographic front view of a further embodiment of the wristwatch of the present invention showing our new design;
FIG. 18 is a photographic rear view thereof;
FIG. 19 is a photographic left side view thereof;
FIG. 20 is a photographic right side view thereof;
FIG. 21 is a photographic bottom view thereof;
FIG. 22 is a photographic top view thereof;
FIG. 23 is a photographic front, right, and top perspective view thereof;
FIG. 24 is an enlarged, photographic, partial front view thereof;
FIG. 25 is a photographic front view of a further embodiment of the wristwatch of the present invention showing our new design;
FIG. 26 is a photographic rear view thereof;
FIG. 27 is a photographic left side view thereof;
FIG. 28 is a photographic right side view thereof;
FIG. 29 is a photographic bottom view thereof;
FIG. 30 is a photographic top view thereof;
FIG. 31 is a photographic front, right, and top perspective view thereof; and
FIG. 32 is an enlarged, photographic, partial front view thereof;
FIG. 33 is a photographic front view of a further embodiment of the wristwatch of the present invention showing our new design;
FIG. 34 is a photographic rear view thereof;
FIG. 35 is a photographic left side view thereof;
FIG. 36 is a photographic right side view thereof;
FIG. 37 is a photographic bottom view thereof;
FIG. 38 is a photographic top view thereof;
FIG. 39 is a photographic front, right, and top perspective view thereof; and
FIG. 40 is an enlarged, photographic, partial front view thereof;
FIG. 41 is a photographic front view of a further embodiment of the wristwatch of the present invention showing our new design;
FIG. 42 is a photographic rear view thereof;
FIG. 43 is a photographic left side view thereof;
FIG. 44 is a photographic right side view thereof;
FIG. 45 is a photographic bottom view thereof;
FIG. 46 is a photographic top view thereof;
FIG. 47 is a photographic front, right, and top perspective view thereof; and
FIG. 48 is an enlarged, photographic, partial front view thereof;
FIG. 49 is a photographic front view of a further embodiment of the wristwatch of the present invention showing our new design;
FIG. 50 is a photographic rear view thereof;
FIG. 51 is a photographic left side view thereof;
FIG. 52 is a photographic right side view thereof;
FIG. 53 is a photographic bottom view thereof;
FIG. 54 is a photographic top view thereof;

FIG. 55 is a photographic front, right, and top perspective view thereof; and
FIG. 56 is an enlarged, photographic, partial front view thereof;
FIG. 57 is a photographic front view of a further embodiment of the wristwatch of the present invention showing our new design;
FIG. 58 is a photographic rear view thereof;
FIG. 59 is a photographic left side view thereof;
FIG. 60 is a photographic right side view thereof;
FIG. 61 is a photographic bottom view thereof;
FIG. 62 is a photographic top view thereof;
FIG. 63 is a photographic front, right, and top perspective view thereof; and
FIG. 64 is an enlarged, photographic, partial front view thereof;
FIG. 65 is a photographic front view of a further embodiment of the wristwatch of the present invention showing our new design;
FIG. 66 is a photographic rear view thereof;
FIG. 67 is a photographic left side view thereof;
FIG. 68 is a photographic right side view thereof;
FIG. 69 is a photographic bottom view thereof;
FIG. 70 is a photographic top view thereof;
FIG. 71 is a photographic front, right, and top perspective view thereof; and
FIG. 72 is an enlarged, photographic, partial front view thereof;
FIG. 73 is a photographic front view of a further embodiment of the wristwatch of the present invention showing our new design;
FIG. 74 is a photographic rear view thereof;
FIG. 75 is a photographic left side view thereof;
FIG. 76 is a photographic right side view thereof;
FIG. 77 is a photographic bottom view thereof;
FIG. 78 is a photographic top view thereof;
FIG. 79 is a photographic front, right, and top perspective view thereof; and
FIG. 80 is an enlarged, photographic, partial front view thereof;
FIG. 81 is a photographic front view of a further embodiment of the wristwatch of the present invention showing our new design;
